CLAIM

We claim the ornamental design for a cutter, as shown and described.

DESCRIPTION

FIG. 1 is a rear perspective view of a cutter according to a first embodiment.

FIG. 2 is a right side view of the cutter of FIG. 1.

FIG. 3 is a left side view of the cutter of FIG. 1.

FIG. 4 is a front view of the cutter of FIG. 1.

FIG. 5 is a rear view of the cutter of FIG. 1.

FIG. 6 is a top view of the cutter of FIG. 1; and,

FIG. 7 is a bottom view of the cutter of FIG. 1.

The portions of the cutter shown in broken lines form no part of the claimed design, including the dash-dot lines used as boundary lines.
